US0D1022211S

(12) **United States Design Patent** (10) **Patent No.:** **US D1,022,211 S**
(45) **Date of Patent:** **** Apr. 9, 2024**

(54) **ULTRAVIOLET IRRADIATOR**

(71) Applicant: **FUJIFILM CORPORATION**, Tokyo (JP)

(72) Inventor: **Takuro Iwaki**, Kanagawa (JP)

(73) Assignee: **FUJIFILM CORPORATION**, Tokyo (JP)

(**) Term: **15 Years**

(21) Appl. No.: **29/829,084**

(22) Filed: **Mar. 2, 2022**

(30) **Foreign Application Priority Data**
